UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed December 7, 1925. Serial No. 73,687.

This invention relates to flexible outside metal car roofs wherein metal roof sheets extend from eaves to ridge of the car and are connected to the car and to each other at the ridge in a manner adapted to permit each sheet to slue or oscillate about a point midway of its ridge end in accommodating itself to the distortions of the car frame; and it relates particularly to ridge construction of roofs of this type. Heretofore, in this type of roof, it has been considered impracticable to provide the sheets with overlapping ridge seam flanges; and the principal object of the present invention is to provide a simple and efficient arrangement that will enable sheets having overlapped ridge seam flanges to pivot or oscillate around a region near the middle of their ridge ends whenever there is movement of said sheets. Another object is to prevent damage to the sheets during such movement. Other objects are reduced cost of manufacture, fewness of parts and compactness of design.

The invention consists principally in a flexible outside metal car roof comprising roof sheets that extend from eaves to ridge and have overlapped ridge seam flanges that are covered by fixed ridge seam covers, the side walls of said overlapped ridge seam flanges and said ridge seam covers being normally in contact with each other at their middle portions only, thereby permitting a limited angular adjustment of said sheets relative to each other and to said seam covers in response to the weaving of the car frame. The invention also consists in the construction and combinations of parts hereinafter described.

In the accompanying drawing, which forms part of this specification and wherein like symbols refer to like parts wherever they occur,

Fig. 1 is a plan view of a flexible outside car roof embodying my invention, the parts being shown broken away to more clearly illustrate the invention;

Fig. 2 is a vertical cross-section through the ridge portion of the roof intermediate the transverse seams thereof on the line 2—2 in Fig. 1;

Fig. 3 is a similar cross-section taken adjacent to one of the transverse seams on the line 3—3 in Fig. 1;

Fig. 4 is a vertical cross-section through

one of the transverse seams on the line 4—4 in Fig. 1;

Fig. 5 is a vertical section through the eaves portion of the car on the line 5—5 in Fig. 1; and

Fig. 6 is a plan view showing the cooperating ridge flanges of adjacent sheets.

Referring to the accompanying drawing, my invention is shown applied to the ordinary type of car comprising roof sheathing 10, supported on side plates 11 and a ridge pole 12. Metal roof sheets 13 extend transversely of the car from eaves to ridge thereof and are provided at their ridge ends with inverted channel-shaped flanges that are lapped to form ridge seams or joints 14 that are covered by inverted channel-shaped ridge seam caps or covers 15. At the eaves, the roof sheets are loosely secured to the car by means of angle flashing strips 16 that are nailed to the sides of the car and have doubled-back flanges that rest on the roof sheathing and cooperate with doubled-under eaves portions 17 of the roof sheets. The sheets are spaced apart at their sides, and between the spaces thus formed are secured mullions or battens 18 that extend from eaves to eaves of the car and are of less width than the spaces between said sheets. The side margins of adjacent sheets, together with the mullions located therebetween, are covered by transverse seam caps or covers 19 of substantially inverted channel-shaped section. These seam caps are preferably provided with inwardly and upwardly extending hooked flanges 20 adapted to interlock with upstanding hooked side seam flanges 21 of the roof sheets. The transverse seam covers 19 are held down on the car at the eaves by turning their eaves ends under the mullions, or in any other desired manner.

As shown in the drawing, the ends of adjacent ridge seam caps 19 and the ridge ends of adjacent transverse seam caps 15 are secured in position by the usual pan-shaped four-way center or corner caps 22. Running boards 23 extend longitudinally of the ridge and are secured to running board saddles 24, which rest on the transverse seam caps and are supported on mullions arranged therebeneath, thus permitting movement of the sheets under the transverse and rigid seam caps. The running board saddles are

secured to the sub-structure by saddle bolts 25 which also secure the corner caps 22 in position.

The inner or underlapping ridge seam flanges 14^a of the roof sheets are of uniform width from end to end and the outer or overlapping ridge seam flanges 14^b closely embrace the middle portion of said inner seam flanges and diverge therefrom towards each end thereof; and likewise the fixed ridge seam caps 15 are made wider at their ends than at their middle so as to limit their contact with said overlapping ridge seam flanges to the narrow middle portions thereof. By this arrangement, the ridge seam caps and the overlapped ridge seam flanges of each pair of roof sheets have a snug fit near their middle portions and are normally spaced apart at their ends, whereby the sheets are forced to roll or rock about the contact portions of their lapped ridge flanges whenever there is movement of said sheets. Thus, such sheets are adapted for limited independent sluing movement about the contacting portions of their overlapped ridge flanges in accommodating themselves to the distortions of the car frame. It is noted that the hereinbefore described ridge seam construction secures a pivotal or sluing movement of sheets whose adjacent marginal portions are provided with hollow ribs that are lapped to form weatherproofing seams, which form of seam is superior to the seam constructions heretofore required for securing such movement of the roof sheets.

The invention is applicable to roofs having various designs of transverse seam and eaves constructions; therefore, I do not wish to be limited to the precise arrangements shown.

What I claim is:—

1. A flexible outside metal car roof comprising roof sheets arranged on the car side by side and provided along their adjacent margins with hollow ribs that are overlapped to form seams, and means whereby said sheets are adapted for independent sluing movement between the side walls of their overlapped ribs whenever there is movement of the sheets.

2. A flexible outside metal car roof comprising roof sheets extending from eaves to ridge of the car and provided at their ridge margins with hollow ribs that are overlapped to form ridge seams, a fixed ridge cover straddling said ribs, and means whereby said sheets are adapted for independent sluing movement between the side walls of their lapped ribs whenever there is movement of said sheets.

3. A flexible outside metal car roof com-

prising roof sheets arranged on the car side by side and formed along their adjacent margins with hollow ribs that are overlapped to form seams, and means for securing an independent oscillatory movement of said sheets between the sides of the overlapped ribs.

4. A flexible outside metal car roof comprising roof sheets arranged on the car side by side, the adjacent marginal portions of said sheets being provided with hollow ribs that are overlapped to form seams, the sides of said overlapped ribs having approximate contact with each other at their middle portions and being normally spaced apart at their ends.

5. A flexible outside metal car roof comprising metal roof sheets whose adjacent margins are provided with hollow ribs that are lapped to form seams, the sides of said lapped hollow ribs diverging from each other from the middle thereof towards the ends thereof.

6. A flexible outside metal car roof comprising metal roof sheets whose adjacent marginal portions are provided with hollow ribs that are lapped to form seams, the underlapping rib of one sheet being of substantially uniform width from end to end and the overlapping rib of the other sheet having approximate contact with the sides of said underlapping rib at the middle thereof and being normally spaced therefrom at the ends thereof.

7. A flexible outside metal car roof comprising roof sheets whose adjacent marginal portions are provided with hollow ribs that are lapped to form seams, and a fixed seam cover covering said seams, said seam cover closely embracing the overlapping rib at the middle thereof and being normally spaced therefrom at the ends thereof and said overlapping rib closely embracing said underlapping rib at the middle thereof and being normally spaced therefrom at the ends thereof.

8. A flexible outside metal car roof comprising roof sheets extending from eaves to ridge of the car and having hollow ribs at their ridge margins that are overlapped, and a ridge seam cover fixed to the car and straddling said overlapped ribs, said seam cover closely embracing the overlapping rib at the middle thereof and being normally spaced therefrom at the ends thereof and said overlapping rib closely embracing said underlapping rib at the middle thereof and being normally spaced therefrom at the ends thereof.

Signed at New Kensington, Pa., this 30th day of November, 1925.

CHARLES DAVID BONSALL.
